COMBINATION DRILL AND SCREW DRIVER

Dean A. Henggeler, 6213 Gladston St., Lincoln, Nebr.

Filed June 7, 1965, Ser. No. 85,590

Term of patent 14 years

(Cl. D54—14)

FIG. 1

FIG. 2

FIG. 3

FIGURE 1 is a front elevational view of my novel combination drill and screw driver;

FIG. 2, a side elevational view thereof; and

FIG. 3, a top plan view.

The broken line showing of tool bits and a power cord in FIGS. 1 and 2 is for illustrative purposes only.

I claim:

The ornamental design for a combination drill and screw driver, as shown and described.
